(57) **CLAIM**

The ornamental design for a shooting bench compartment, as shown and described.

DESCRIPTION

FIG. 1 is a rear, right perspective view of a shooting bench compartment embodying our new design as shown in an extended position.

FIG. 2 is a right side elevational view thereof.

FIG. 3 is a left side elevational view thereof.

FIG. 4 is a top view thereof.

FIG. 5 is a bottom view thereof.

FIG. 6 is a front elevational view thereof; and,

FIG. 7 is a rear elevational view thereof.

The broken lines shown on the drawing disclosure are for illustrative purposes only and form no part of the claimed design.
